Fig. 1.

Fig. 2.

Fig. 3.

Fig. 4.

FIGURE 1 is a perspective view of a furniture pedestal showing my design, an outline of a circular transparent table top having been shown therein for illustrative purposes only;

This application is a continuation-in-part of my co-pending application Serial No. D. 86,788, filed Aug. 31, 1965, for an article of furniture, and now Patent No. D. 211,463.

I claim:

The ornamental design for a pedestal or the like, as shown.
